UNITED STATES PATENT OFFICE.

HEIMI WEISINGER, OF NEW YORK, N. Y.

DESIGN FOR A LADY'S FELT SLIPPER.

Application filed July 3, 1923. Serial No. 6,666. Term of patent 3½ years.

To all whom it may concern:

Be it known that I, HEIMI WEISINGER, residing at New York, county and State of New York, have invented a certain new, original, and ornamental Design for Ladies' Felt Slippers, of which the following is a specification, reference being had to the accompanying drawing, forming part thereof.

I claim:

The ornamental design for a lady's felt slipper, as shown.

HEIMI WEISINGER.

Witnesses:

EMMA WEINBERG,
ANGELO DE LUCCA.
